UNITED STATES PATENT OFFICE

GUSTAV RICHARD CARL, OF CHICAGO, ILLINOIS

WINDOW CONSTRUCTION

Application filed April 29, 1929. Serial No. 358,967.

My invention relates to window constructions, and more particularly to improvements in windows such as that shown in my prior application Serial No. 225,744.

5 The principal purpose of this invention is to provide a novel means for connecting the hinge pins at the hinged side of the window so as to facilitate the operation of the window when it is desired to swing it about a horizontal axis.

10 It is a further purpose of this invention to provide such a construction in which the unsightly elements of the hardware used in mounting the window are so arranged as to 15 be substantially hidden from view.

Other objects and advantages of the invention will appear as the description proceeds, in connection with the accompanying drawings.

20 It is to be understood, however, that I do not intend to limit myself to the details shown and described, but that I intend to avail myself of all such modifications as would occur to one skilled in this art and as fall within 25 the scope of the claims.

In the drawings,—

Fig. 1 is a front view of a window such as shown in my prior application, with the improvements hereinbefore mentioned thereon; 30 Fig. 2 is a section on the line 2—2 of Fig. 1; Fig. 3 is a section on the line 3—3 of Fig. 1; Fig. 4 is a section on the line 4—4 of Fig. 1; and

35 Fig. 5 is an enlarged detail section of one of the hinges.

Referring now in detail to the drawings, I show at 6 a window casing in which the window 7 is so mounted, as will be herein-after more fully described, as to be swingable about both a horizontal and vertical axis. Within the window 7 there is also slidably mounted a sash 8 which swings with and forms a part of the main window 7, as is clearly brought out in my prior application.

40 It will be noted that certain brackets, as indicated at 9, 10 and 11, are secured to the casing 6 and provided with sockets to receive the hinge pins 12, 13 and 14, which hinge pins also pass through the sleeves 15, 16 and 45 17 that are mounted, respectively, on the

brackets 18, 19 and 20. The brackets 18 and 20, as shown, are secured to the window 7 in such manner as to be concealed from the interior of the room in which the window is mounted by means of the overhanging lip portion 21, which extends completely around the frame of the window 7. Bracket 19, of course, carries also the locking member 22 for locking the sash 8 in various positions, so that this bracket is exposed on the face of the window.

The hinge pins 12, 13 and 14, in the normal position, of course, hinge the window so that it may be swung about a vertical axis. Now, however, when it is desired to tip the window about a horizontal axis, pins 13 and 14 are so arranged that they may be removed from the sockets on the brackets 10 and 11, and the pin 12 is adapted to be adjusted in such a manner as to co-operate with the fixture illustrated at 23 to form means for permitting a limited amount of swinging movement of the window about its lower edge.

Now, if it were necessary to reach to the top of the window to lift up the pin 14 each time the window is to be swung outwardly about a horizontal axis, considerable difficulty would be encountered in the operation of the window. In order to avoid this difficulty, pins 13 and 14 are connected by means of a rod 25, which, as shown clearly in Fig. 1, extends laterally from the pin 13 into a slot 26 provided along the side edge of the frame of the window 7, and then upwardly in this slot, as shown clearly at 27 in Figs. 1 and 3, to a point a short distance below the sleeve 17 of bracket 20. At this point the rod 25 extends outwardly again substantially horizontally, as at 28, and then vertically to connect with the lower end of the pin 14. The socket in the bracket 11 is, of course, provided with a slot 29, which is slightly larger than the diameter of the rod 25, so that when the pin 14 is elevated this rod may pass outwardly through the slot.

The rod 25, being concealed throughout the greater portion of its length, presents no unsightly appearance, and at the same time performs its function efficiently by maintaining the pin 13 in the proper position to be

55

100

easily lifted by the hand of the person opening the window.

The horizontal portion 28 of this rod also co-operates with a stop 30 mounted in the 5 groove 26 to limit the upward movement of the pins 13 and 14 so as to prevent moving these pins laterally out of the sleeves 16 and 17.

The pin 12 has a stop member 31 thereon, 10 which, in one position of the pin 12, is adapted to slide in the keyway or groove 32 of sleeve 15 so as to permit the pin to pass into the position shown in Fig. 1. Now, however, in preparing the window for 15 swinging about its horizontal axis, the pin 12 is lifted to bring the stop 31 above the top of the sleeve 15, and then the pin is turned to bring the stop out of alignment with the groove 32, which properly positions the 20 round disk-like head 33 provided at the end of the reduced extension 34 of this pin, so that this disk-like head 33 will engage in the slot 35 provided in the bracket 9.

With the pin in the uppermost position 25 just described, the reduced portion 34 may then swing outwardly into the slot 36 to the position shown in Fig. 5, thus permitting the window to swing about its lower edge outwardly away from the casing 6.

30 The fixture 23, of course, with the co-operating bracket 24, operates in substantially the same manner as that shown in the prior application, and, of course, suitable latching means may be provided, as in this prior application, for holding the window in partially open position.

It will be noted, however, that the actual operations which much be performed, even 40 in swinging a large window such as this outwardly at the top, are comparatively simple and easy to perform. All that is necessary is to properly place the elements 23 and 24 into contact with each other, lift and set the pin 12 as described, and then, by grasping 45 the handle of the pin 13, lift both pins 13 and 14 out of their respective sockets in the casings 10 and 11. The window is then free to swing outwardly at the top through the limited distance allowed by the securing 50 means at the bottom and any latch means that is provided.

From the above description, it is thought that the construction and advantages of this device will be clear to those skilled in this art, 55 and having thus described my invention, what I claim as new and desire to secure by Letters Patent is:

1. A device of the character described, a 60 window casing, a window and means connecting said window to said casing for swinging movement about a horizontal and about a vertical axis comprising hinge members at one side of said window having pins movable from a position permitting horizontal swinging of said window to a position permitting

70 swinging of said window about a horizontal, and means connecting a pair of said pins, said means being concealed in the frame of said window between said pins.

2. A device of the character described, a 75 window casing, a window and means connecting said window to said casing for swinging movement about a horizontal and about a vertical axis comprising hinge members at one side of said window having pins movable from a position permitting horizontal swinging of said window to a position permitting 80 swinging of said window about a horizontal, and means connecting a pair of said pins, said means being concealed in the frame of said window between said pins, and stop means on said frame cooperating with said connecting means to limit the movement of said pins.

3. A device of the character described, a 85 window casing, a window and means connecting said window to said casing for swinging movement about a horizontal and about a vertical axis comprising hinge members at one side of said window having pins movable from a position permitting horizontal swinging of said window to a position permitting 90 swinging of said window about a horizontal, and means connecting a pair of said pins, said means being concealed in the frame of said window between said pins, one of said hinge members having means limiting the swinging 95 of said window about a horizontal axis.

4. A device of the character described, a 100 window casing, a window and means connecting said window to said casing for swinging movement about a horizontal and about a vertical axis comprising hinge members at one side of said window having pins movable from a position permitting horizontal swinging of said window to a position permitting 105 swinging of said window about a horizontal, and a rod connecting a pair of said pins, said rod being concealed in the frame of said window below said pins.

5. A device of the character described, a 110 window casing, a window and means connecting said window to said casing for swinging movement about a horizontal and about a vertical axis comprising hinge members at one side of said window having pins movable from a position permitting horizontal swinging of said window to a position permitting 115 swinging of said window about a horizontal, and a rod connecting a pair of said pins, said rod being concealed in the frame of said window between said pins, and stop means also concealed in said frame cooperating with said connecting rods to limit the movement of said pins.

6. A window construction of the character described comprising a window hinged to a casing by hinge members certain of which have readily separable elements, and another of which has one socket member provided 125 130

with a reduced wedge shaped interior groove extending from one end, and a transverse slot intermediate its ends, and a hinge pin provided with a disk shaped portion at its lower end for engagement with said slot and a reduced portion adjacent said portion for engagement in said groove.

In witness whereof, I hereunto subscribe my name this 18th day of April, A. D. 1929.

GUSTAV RICHARD CARL.
